(57) **CLAIM**

The ornamental design for a tripod mount, as shown and described.

DESCRIPTION

FIG. 1 is a front, left, top perspective view of the tripod mount in the first state, showing my new design;

FIG. 2 is a rear, right, bottom perspective view thereof;

FIG. 3 is a front, right, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a front, left, top perspective view of the tripod mount in the second state;

FIG. 11 is a front, left, top perspective view of the tripod mount in the third state;

FIG. 12 is an enlarged view of detail 12 in FIG. 1;

FIG. 13 is an enlarged view of detail 13 in FIG. 1;

FIG. 14 is an enlarged view of detail 14 in FIG. 1;

FIG. 15 is an enlarged view of detail 15 in FIG. 2;

FIG. 16 is an enlarged view of detail 16 in FIG. 2;

FIG. 17 is an enlarged view of detail 17 in FIG. 4;

FIG. 18 is an enlarged view of detail 18 in FIG. 5;

FIG. 19 is an enlarged view of detail 19 in FIG. 5;

FIG. 20 is an enlarged view of detail 20 in FIG. 6;

FIG. 21 is an enlarged view of detail 21 in FIG. 6;

FIG. 22 is an enlarged view of detail 22 in FIG. 6;

FIG. 23 is an enlarged view of detail 23 in FIG. 7;

FIG. 24 is an enlarged view of detail 24 in FIG. 8;

FIG. 25 is an enlarged view of detail 25 in FIG. 9; and,

FIG. 26 is an enlarged view of detail 26 in FIG. 9.

The dashed broken lines illustrate portions of the tripod mount which form no part of the claimed design.

The dash-dot-dash broken lines are for notating enlarged views and form no part of the claimed design.

1 Claim, 23 Drawing Sheets
